United States Patent

Des. 239,500
Patented Apr. 13, 1976

239,500

SLIDE HOOK

Allen J. Rose, Chicago, Ill., assignor to ACCO
International Inc., Chicago, Ill.

Filed Sept. 23, 1974, Ser. No. 508,465

Term of patent 14 years

Int. Cl. D8—07

U.S. Cl. D8—109

FIG. 1 is a perspective view of a slide hook embodying my new design;

FIG. 2 is a top plan view thereof;

FIG. 3 is an elevational view of one of the two like ends thereof;

FIG. 4 is a bottom plan view thereof;

FIG. 5 is an enlarged end view thereof as seen along line 5—5 of FIG. 2; and

FIG. 6 is an enlarged end view thereof as seen along line 6—6 of FIG. 2.

I claim:

The ornamental design for a slide hook, substantially as shown.
